TOY PISTOL

Ernest H. Bergstrom, Dorchester, Mass.

Application April 18, 1934, Serial No. 721,120

12 Claims. (Cl. 273—129)

This invention relates to toy pistols and has for its object the provision of an article of this character especially adapted for propelling marbles along a substantially horizontal surface into a goal member disposed upon said surface thereby providing entertainment for children.

This object is attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

20 Of the drawing

Figure 1 represents an elevation of a toy pistol embodying the principles of the present invention.

Figure 2 represents an elevation of the lower end of same with the supporting foot thereof removed.

Figure 3 represents an elevation of a goal member used in connection with said pistol.

Figure 4 represents an end elevation of the pistol.

Figure 5 represents a vertical section of same on line 5, 5 on Fig. 4, and

Figure 6 represents an inverted plan of the pistol.

Figures 4, 5 and 6 are shown drawn to an enlarged scale.

Similar characters indicate like parts throughout the several figures of the drawing.

In the drawing, 10 is a chambered housing having a barrel portion 11 and a handle portion 12.

This housing is made of two parts secured together in any well known manner.

Within the chamber 13 of the housing 10 is disposed a slidable member 14 having a finger 15 projecting from said housing through an elongated slot 16.

The lower end 17 of the slidable member 14 is inclined as indicated in Fig. 5 of the drawing.

One edge of the slidable member 14 bears against the inner wall of the housing 10 and the opposite edge has shoulders 18 and 19 coacting with inwardly extending projections 20 and 21 formed upon said housing and limiting the movement of said slidable member 14 in either direction.

The member 14 is provided with an upwardly

extending arm 22 in one edge of which is formed a plurality of ratchet teeth 23 and pivoted at 24 and disposed within the chamber 13 is a pawl member 25 adapted to coact with the teeth 23.

The upper end 26 of this pawl member 25 extends through a slot 27 in the housing 10.

One face of the end 26 is knurled as at 28, thereby forming a gripping surface by which the pawl 25 may be moved about the pivot 24 to release said pawl from engagement with the teeth 23.

The pawl 25 is normally retained in contact with the teeth 23 by means of a spring member 29 coiled about a stud 30 with one arm 31 thereof bearing against another stud 32, these studs 30 and 31 being formed upon the inner wall of one part of the housing 10.

Secured at one end to the finger 15 is a helical spring 33 the opposite end of which is secured to an ear 34 formed upon the lower wall 35 of the housing 10.

This spring 33 tends to pull the slidable member 14 downwardly into the position shown in Fig. 5 of the drawing.

Bearing against the inclined edge 17 of slidable member 14 is a cone-shaped head 36 of a plunger 37 disposed substantially perpendicular to the barrel portion 11 of the housing 10.

Between the inner wall of the housing 10 and the head 36 of said plunger is a spring 38, the tension of which will retain the plunger 37 in retracted position when the slidable member 14 is withdrawn from the path thereof.

The lower end of the barrel portion 11 is wholly enclosed by the wall 35 and from this wall 35 extends two headed studs 39 adapted to coact with keyhole slots 40 in a supporting plate 41.

This plate 41 is bifurcated as at 42 thereby forming a track on which a marble 43 may be disposed when the pistol is to be used.

In connection with the pistol a goal member 44 is used which is made of lead or other heavy metal and is disposed on a substantially horizontal surface 46.

This goal member 44 is circular with inclined sides and a central depression 45 as shown in Fig. 3 of the drawing.

When the pistol is in use the supporting plate 41 is disposed upon the horizontal surface 46 at any desired distance from the goal member 44, as shown in Fig. 1 of the drawing.

The operator then by grasping the handle portion 12 and pulling the finger 15 towards the handle, the slidable member 14 may be raised

any desired distance to permit the pawl 25 to contact with either of the ratchet teeth 23.

As soon as this member 14 is thus raised the spring 38 will force the plunger 37 inwardly.

5 A marble 43 is then placed on the track 42 and the plunger 37 pointed toward the goal member 44.

When this has been done the operator may place his thumb on the knurled upper end 28 of the pawl 25 and release the pawl from the teeth 23.

10 As soon as this is accomplished the spring 33 will move the slideable member 14 downwardly with sufficient force to cause the plunger 37 to be quickly moved outwardly.

In doing this it will cause the marble to be shot 15 from the track 42 toward the goal 44.

By moving the slideable member to its upward limit and then releasing the said slideable member, a greater force will be imparted to the plunger 37 and the marble hit thereby will be moved a greater 20 distance.

By moving the slideable member 14 upwardly a lesser distance less force will be imparted to the plunger 37 when said member 14 has been released, thus moving the marble a shorter distance.

25 In using the toy pistol obviously at the beginning of the game, it is desired to move the marbles as great a distance as possible toward the goal and as this marble stops at points nearer the goal a lesser force is necessary to cause the marble to move over the shorter distance from said goal.

In other words, by means of the plurality of teeth 23 any given stroke against the marble may be provided for.

The supporting member 41 is ordinarily in use 35 on the housing but when the marble stops in a slight depression, this supporting member 41 may be removed so that the lower end of the housing may be moved downwardly into the depression and then shoot the marble by a sudden outward movement of the plunger 37.

As soon as the marble becomes disposed on a level surface again the supporting member 41 is returned to its normal position.

This toy pistol for shooting marbles towards a 45 goal will afford a great deal of amusement to children.

The device may be cheaply constructed and sold to children at a low price.

It is believed that the operation and many advantages of the invention will be understood without further description.

Having thus described my invention, I claim:

1. In a device of the class described, an elongated chambered housing; a plunger perpendicular to and near one end of said housing; a spring surrounding and normally retaining said plunger in retracted position; and movable means in said housing for forcing said plunger outwardly against the tension of said spring.

60 2. In a device of the class described, an elongated chambered housing; a plunger perpendicular to and near one end of said housing; means within said housing for normally retaining said plunger in retracted position; and a spring-actuated member within said housing coacting with the inner end of said plunger and adapted, when released, to be moved downwardly by said spring and force said plunger outwardly.

70 3. In a device of the class described, an elongated chambered housing; a plunger perpendicular to and near one end of said housing; means for normally retaining said plunger in retracted position; a wedge member in said housing coacting with the inner end of said plunger for forcing said plunger outwardly and having a finger by

which it may be moved in one direction; a spring for moving said member in the opposite direction; and releasable means for retaining said wedge member in retracted position.

4. In a device of the class described, an elongated chambered housing; a plunger perpendicular to and near one end of said housing; means within said housing for normally retaining said plunger in retracted position; a spring-actuated member within said housing coacting with the inner end of said plunger and adapted, when released, to force said plunger outwardly, said member being provided with a plurality of ratchet teeth; and a pivoted pawl coacting with said teeth to retain said member in retracted position. 10

15 5. In a device of the class described, a housing formed with a barrel portion and a handle portion; a plunger perpendicular to and near the outer end of said barrel portion; means for normally retaining said plunger in retracted position; a slideable member in said barrel portion adapted to force said plunger outwardly during its forward movement; a spring for moving said member forward.

20 6. In a device of the class described, a housing formed with a barrel portion and a handle portion; a plunger perpendicular to and near the outer end of said barrel portion; means for normally retaining said plunger in retracted position; a slideable member in said barrel portion adapted to force said plunger outwardly during its forward movement; a spring for moving said member forward; means for moving said member rearwardly; and releasable means for holding said member in its rearward position against the tension of said spring. 25

7. In a device of the class described, a housing formed with a barrel portion and a handle portion; a plunger perpendicular to and near the outer end of said barrel portion; a spring for normally retaining said plunger in retracted position; a slideable member in said barrel portion coacting with the inner end of said plunger and adapted to force it outwardly, said member having a finger beneath said barrel portion by which said member may be moved in one direction; a spring for moving said member in the opposite direction; and a spring-actuated pivoted holding device for retaining said member in retracted position. 40

50 8. In a device of the class described, a housing formed with a barrel portion and a handle portion; a plunger perpendicular to and near the outer end of said barrel portion, said plunger having a conical head at its inner end; a spring coacting with said head for normally retaining said plunger in retracted position; a slideable member in said barrel portion having an inclined surface coacting with the conical head of said plunger and adapted to force it outwardly, said member having a finger beneath said barrel portion by which said member may be moved in one direction; a spring for moving said member in the opposite direction, and a spring-actuated pivoted holding device for retaining said member in retracted position. 55

60 9. In a device of the class described, a housing formed with a barrel portion and a handle portion; a plunger perpendicular to and near the outer end of said barrel portion, said plunger having a conical head at its inner end; a spring for normally retaining said plunger in retracted position; a slideable member in said barrel portion having an inclined surface coacting with the inner end of said plunger and adapted to force 65

it outwardly, said member having a plurality of ratchet teeth; a spring for moving said member downwardly; and a spring-actuated pivoted pawl coacting with said teeth to retain said member in retracted position.

10. In a device of the class described, a housing formed with a barrel portion and a handle portion; a plunger movable in a bearing perpendicular to and near the outer end of said barrel portion, normally retained in retracted position; mechanism within said housing under tension including a wedge member contacting with the end of said plunger and adapted to force said plunger outwardly; and a marble-holding track member secured to the end of said barrel portion and parallel with said plunger.

11. In a device of the class described, a housing formed with a barrel portion and a handle portion; a plunger movable in a bearing perpen-

dicular to and near the outer end of said barrel portion; a light spring for normally retaining said plunger in retracted position; mechanism within said housing under tension of a heavy spring and adapted, when released, to force said plunger outwardly; and a forked marble-holding track member secured to the end of said barrel portion and parallel with said plunger. 5

12. In a device of the class described, a housing formed with a barrel portion and a handle portion; a plunger perpendicular to and near the outer end of said barrel portion normally retained in retracted position; mechanism within said housing under tension and adapted, when released, to force said plunger outwardly; and 10 15 a marble-holding track member removably secured to the end of said barrel portion and parallel with said plunger.
